(57) **CLAIM**

The ornamental design for an automotive wrench, as shown and described.

DESCRIPTION

FIG. 1 is a left perspective side view of an automotive wrench showing the opening of the jaws;

FIG. 2 is a right side view of an automotive wrench of FIG. 1 showing the opening of the jaws thereof;

FIG. 3 is a left side view of the design of FIG. 2 showing the jaws gripping an object shown in broken lines;

FIG. 4 is a left side view of the design of FIG. 2 showing the jaws gripping a further object shown in broken lines;

FIG. 5 is a top plan view of the design of FIG. 2;

FIG. 6 is a bottom plan view of the design of FIG. 2;

FIG. 7 is a rear view of the jaws of FIG. 2 thereof;

FIG. 8 is a front view of the jaws of FIG. 2 thereof;

FIG. 9 is a perspective side view of the design of FIG. 2 thereof;

FIG. 10 is a first variant of an automotive wrench showing a perspective side view with the opening of the jaws thereof;

FIG. 11 is a right side view of the automotive wrench of FIG. 10 showing the opening of the jaws thereof;

FIG. 12 is a front view of the automotive wrench of FIG. 10;

FIG. 13 is a left side view of the design of FIG. 10 showing the jaws gripping an object shown in broken lines;

FIG. 14 is a left side view of the design of FIG. 10 showing the jaws gripping a further object shown in broken lines;

FIG. 15 is a top plan view of the design of FIG. 10;

FIG. 16 is a bottom plan view of the design of FIG. 10;

FIG. 17 is a rear view of the jaws of FIG. 10 thereof; and,

(Continued)

FIG. 18 is a left perspective side view of the design of FIG. 10 thereof.
